UNITED STATES PATENT OFFICE

JOHN L. HUNTER, OF WAUKEGAN, ILLINOIS, ASSIGNOR TO AHLBELL BATTERY CONTAINER CORPORATION, OF WAUKEGAN, ILLINOIS, A CORPORATION OF ILLINOIS

PRESS FOR PLASTIC MATERIAL

Application filed April 26, 1930. Serial No. 447,590.

My invention relates more particularly to presses for use in the manufacture of containers formed from moldable material such as for example and more especially asphaltic compositions, the invention having been devised for use more especially in the manufacture of storage battery containers provided to receive the battery elements thereof and forming containers therefor and for the electrolytes.

My primary objects are to provide a machine by which the cost of manufacture of containers, especially battery containers, may be reduced; to provide a machine which shall be of comparatively simple and economical construction, positively operating, and by the use of which loss due to breakage of the containers will be reduced to the minimum; and other objects as will be manifest from the following description.

Referring to the accompanying drawings: Figure 1 is a view in sectional elevation of a machine embodying my invention.

Figure 2 is a plan sectional view taken at the line 2—2 on Fig. 1 and viewed in the direction of the arrows.

Figure 3 is a plan sectional view taken at the line 3—3 on Fig. 1 and viewed in the direction of the arrows.

Figure 4 is a perspective view of one of the side-forming plates of the mold constituting a part of the machine.

Figure 5 is a broken enlarged view in sectional elevation, the section being taken at the irregular line 5—5 on Fig. 2 and viewed in the direction of the arrows, the parts shown of the machine being represented in the positions they assume during the molding operation.

Figure 6 is a view like Fig. 5 showing the position assumed by the side-forming plates of the mold upon the movement of the latter to a position for releasing the container formed therein, the container having been removed from the mold.

Figure 7 is a sectional view taken at the line 7—7 on Fig. 1 and viewed in the direction of the arrows.

Figure 8 is a view in vertical sectional ele-

vation of the core structure forming a part of the machine; and

Figure 9, a section taken at the line 9 on Fig. 8 and viewed in the direction of the arrow.

Referring to the particular, illustrated, embodiment of my invention, the machine comprises a base 10 presenting an upwardly opening cylinder 11, upwardly extending rods 12 disposed in rectangular arrangement and rising from the case 10, and a head 13 surmounting, and rigidly connected with, the rods 12 to extend in vertically spaced relation to the base 10.

The machine also comprises a vertically movable ram formed of a piston 14 vertically movable in the cylinder 11 and a head 15 rigidly secured to the top of the piston 14, this ram being adapted to be forced upwardly in the cylinder in any suitable way, as for example by fluid pressure introduced into the bottom of the cylinder 11 through a pipe 16 communicating with any suitable source of air under pressure and having interposed therein a valve device 17 by which air pressure may be supplied to the bottom of the cylinder 11 or permitted to vent therefrom to the atmosphere, as desired.

The head 15 is provided at its top with a portion 18, shown as a part separate from the body portion of the head 15 and forming the bottom of the mold in which the container is to be formed, the member 18 which is of rectangular shape, being provided about its four sides with laterally extending flanges 19.

The sides of the mold are formed of four plates 20 disposed in a rectangular arrangement as shown, the adjacent edges of these plates being stepped to cause them to mutually interfit when in mold-forming position, all as shown more particularly in Fig. 3, each plate 20 having an inturned lip 20^a at its upper edge.

The plates 20 are adapted to be swung, as hereinafter more fully explained, into and out of mold-forming position and to this end each of said plates contains on its inner surface, adjacent its lower end, a groove 21, these plates being assembled with the member 18 in such position that the flanges 19 extend

into the grooves 21 of the respective plates 20.

Surrounding the lower edge portions of the plates 20 is a frame 22 provided with four depending pins 23 slidable in vertical openings 24 in the head 15, the lower ends of these pins opposing the upper surface of a ring 25 surrounding the piston 14 and forming a part of the stationary base structure 10.

The frame 22 contains in its under-surface and about the central opening through the frame, an endless recess 26 in which a frame-like plate 27 is secured as by bolts 28. The member 27 surrounds the lower extremities of the plates 20, the outer surfaces of which are beveled as represented at 30, the opposing surfaces of the walls of the opening in the member 27 being similarly beveled as represented at 31. The arrangement and proportions of the parts just described are such that when the member 22 occupies the position shown in Fig. 5 the plates 20 may occupy the position shown in Fig. 5 without restraint from the plate member 27, but when the plate member 27 is raised relative to the head 15 as hereinafter described and as shown in Fig. 6, the plates 20 will be forced to assume the outwardly swung position represented therein, the plates 20 in such movement swinging about the flanges 19 as fulcrums.

Means are associated with the lower portions of the plates 20 tending to swing them to the closed position shown in Fig. 5, these means comprising T-bolts 32 which extend at their shanks through slots 33 in the lower edges of the plates 20 and interlock at their T-heads 34 with grooves 35 on the inner surfaces of these plates, these shanks extending outwardly through openings 36 in the frame 22, their terminal ends carrying nuts 37 between which and shoulders 38 provided in the openings 36 coil springs 39 surrounding these shanks, extend.

The head 13 is formed to present a vertically extending cylinder 40 in which a piston 41 is vertically movable, this piston being connected with an upwardly extending rod 42 sliding in the upper end wall 43 of the cylinder 40 and connected at its upper, outer, end with a member 44 from which vertical rods 45 depend, the rods 45 being rigidly connected with a die box 46 containing an opening 47 therethrough the axis of which is in vertical alinement with the axis of the piston 14.

The die box 46 is provided for maintaining the side-wall-forming plates 20 of the mold in closed position during the operation of forming the container as hereinafter described, and to this end is adapted to be moved into a position in which it closely surrounds the plates 20 as shown in Fig. 1. The plates 20 are so formed that when in the closed position shown in Fig. 1 their outer surfaces incline toward the vertical axis of the machine as represented at 48 and the wall 49 of the opening 49 in the die box is inclined

at its four sides at a corresponding angle but in the reverse direction as shown.

In the machine shown provision is made for admitting fluid pressure to either end of the cylinder 40 and exhausting the latter as desired, the means shown for this purpose comprising pipes 50 and 51 which open, respectively, into the bottom and top of the cylinder 40 and into a valve casing 51 containing an inlet 52 communicating with a pipe 53 leading to any suitable source of fluid pressure, as for example compressed air. The casing 51 contains a rotatable valve plug 54 containing a straightway port 55 adapted when the valve is moved into one position to cause opposite ends of the cylinder 40 to be in communication with each other. When the valve 54 is rotated counterclockwise in Fig. 1 approximately 45° the port 57 moves into registration with the inlet pipe 53 and the pipe 51, and the port 56 into registration with the pipe 50 and a vent opening 58 in the casing 51 whereby fluid pressure is admitted to the top of the cylinder 40 and the lower portion of this cylinder is vented to the atmosphere. Rotation of the valve 54 in a clockwise direction in Fig. 1 approximately 45° from the position therein shown, causes the port 57 to communicate with the pipes 50 and 53, and the pipe 51 with the outlet 58 whereupon fluid pressure is admitted to the lower end of the cylinder and the upper end of the cylinder is vented to the atmosphere.

The machine also comprises a core supported on the head 13 in axial alinement with the piston 14, and with which the mold structure above described cooperates in the forming of the container, the particular core construction shown comprising three core sections 59 for forming a container presenting three compartments, these core sections being spaced apart as shown, their combined base portions presenting a rectangular structure 60 about which the upper portion 61 of the side wall of the mold structure closely extends when the machine is operated to the position shown in Fig. 5.

In the use of the machine the piston 14 is positioned as shown in Fig. 1, namely, to extend a slight distance above the bottom of the cylinder 40, in which position the mold-side-forming plates 20 extend in mold-forming position as shown, the frame 22 being in lowered position, and the die box 46 surrounding the mold formed of the plates 20, as shown, the upper edges of the plates 20 extending above the upper edge of the die box 46 in this position of the mechanism.

In this position of the parts described the material from which the container is to be formed and which, by way of example may be any suitable asphaltic composition such as that commonly used, is then laid on the upper surface of the bottom-forming plate 18

to extend within the space presented between the plates 20 as shown in Fig. 1.

With the material positioned as stated, fluid pressure is introduced into the bottom 5 of the cylinder 11 which forces the member 15 and the parts carried thereby, together with the die box 46, the rods 45 and the piston 41, upwardly, the upper edges of the plates 20 engaging the base of the core member and 10 the core sections 59 becoming engaged by the mass 62 of the material which latter, under the pressure exerted against it by the core sections, is caused to be forced into all portions 15 of the mold cavity provided between adjacent core sections and between the latter and the wall and bottom-forming portions of the mold as shown in Fig. 5 to form a homogeneous integral mass in the form of the container desired to be produced and 20 represented at 63.

Following the forming of the container as stated, the operator causes the die box 46 to be raised by admitting fluid pressure beneath piston 41 which is effected by actuating the 25 valve 54 in a direction to admit fluid pressure beneath piston 41 which relieves the lateral restraint imposed on the plates 20 by the die box, and thereupon causes the mold structure, with the formed container therein, to lower by opening the cylinder 11 to exhaust which strips the container from the core-sections.

As the piston 14 nears the limit of its movement to lowermost position, the pins 23 about 30 the upper surface of the member 25 whereupon downward movement of the frame 22 is arrested whereby in the continuing lowering of the piston 14, the beveled surfaces 30 of the plates 20 ride against the member 27 thereby producing a camming action against 35 the lower portions of the plates 20 which swing them upon the fulcrum-forming flanges 19 in an outward direction as shown in Fig. 6 thereby releasing the formed container and permitting it to be removed from the machine.

The piston 14 is then slightly raised to the position shown in Fig. 1 in which movement 40 the mold structure rises relative to the frame 22 to the position shown in this figure which permits the springs 39 to rock the mold plates 20 into the mold-forming condition shown in Figs. 1 and 5, whereupon the operator manipulates the valve 54 to lower the die box 46 to the position shown in Fig. 1 for restraining the mold plates 22 against lateral displacement, the structure then being ready 45 to receive another lump of material for forming another container.

By providing the means for admitting fluid pressure above the piston 41, the descent of the die box 46 may be accelerated in the operation above described.

The die-box 46, the lower portion of the 50 head 13 and represented at 64 and the core

structure supported thereon, are shown as provided with passages therein. The passages in the die box 46 are represented at 65 these passages being in communication with each other and with an inlet pipe 66 and an outlet pipe 67. The passages in the member 64 and which are in communication with each other are represented at 68 and are connected with an inlet pipe 69 and an outlet pipe 70; and the passages in the core sections 59 are 70 represented at 71 and communicate with inlet pipes 72 and outlet pipes 73.

It is desirable, in the manufacture of containers from asphaltic compositions that the 75 temperature of the parts of the machine with which the material contacts be that approximating that of the material which is introduced into the machine at approximately 350° F. by way of example. Accordingly, 80 it is desirable that a heating medium be circulated through the passages in the die box 46 prior to the starting of the press into operation, such a medium as for example steam, being introduced into the die box through the pipe 66. Where the conditions are such that 85 continued operation of the press raises the temperature of the structure beyond that desired, any suitable cooling medium may be circulated through the passages in the die 90 box. 95

The machine described is also suited for the manufacture of containers from vulcanizable material in which case any suitable heating medium, as for example steam, may be circulated through the passages in the die box 100 46, member 64 and the passages 71 in the core sections 59, the latter being shown as recessed at 74 to receive electrical heating elements (not shown) for use, if desired, in the vulcanizing of the material. 105

While I have illustrated and described a particular construction embodying my invention, I do not wish to be understood as intending to limit it thereto, as the same may be variously modified and altered without departing from the spirit of my invention. 110

What I claim as new, and desire to secure by Letters Patent, is:

1. In a machine of the character set forth, 115 the combination of receptacle-forming mold and core members, the side walls of said mold member being movable toward and away from each other and said mold member being movable relative to said core member, means for holding said side walls against outward movement in the molding operation, and means engageable with a relatively stationary part of the machine in the movement of said mold member in a direction away from said core member operating automatically to force said side walls outwardly. 120

2. In a machine of the character set forth, 125 the combination of receptacle-forming mold and core members, the side walls of said mold member being movable toward and 130

- away from each other and said mold member being movable relative to said core member, means for holding said side walls against outward movement in the molding operation, 5 and wedging means engageable with a relatively stationary part of the machine in the movement of said mold member in a direction away from said core member operating automatically to force said side walls outwardly. 10 3. In a machine of the character set forth, the combination of receptacle-forming mold and core members, the side walls of said mold member being fulcrumed to swing outwardly and said mold member being movable relative 15 to said core member, means for holding said side walls against outward movement in the molding operation, and means engageable with a relatively stationary part of the machine in the movement of said mold member 20 in a direction away from said core member operating automatically to force said side walls outwardly. 4. In a machine of the character set forth, the combination of receptacle-forming mold 25 and core members, the side walls of said mold member being movable toward and away from each other and said mold member being movable relative to said core member, means for holding said side walls against outward movement in the molding operation, and means surrounding the lower ends of 30 said side walls and engageable with a relatively stationary part of the machine in the movement of said mold member in a direction away from said core member operating automatically to force said side walls outwardly. 5. In a machine of the character set forth, the combination of receptacle-forming mold 40 and core members, the side walls of said mold member being movable toward and away from each other and said mold member being movable relative to said core member, means for holding said side walls against 45 outward movement in the molding operation, and a member carried by said mold member and relative to which said mold member is movable and operative in the movement of said mold member relative thereto to force 50 said side walls outwardly. 6. In a machine of the character set forth, the combination of receptacle-forming mold and core members, the side walls of said mold member being movable toward and away from each other and said mold member being movable relative to said core member, means for holding said side walls against outward movement in the molding operation, means for forcing said side walls toward each other, 55 and means engageable with a relatively stationary part of the machine in the movement of said mold member in a direction away from said core member operating automatically to force said side walls outwardly against the resistance of said second-named means. 7. In a machine of the character set forth, the combination of receptacle-forming mold and core members, the side walls of said mold member being movable toward and away from each other and said mold member being movable relative to said core member, means for holding said side walls against outward movement in the molding operation, means for forcing said side walls toward each other, and wedging means engageable with a relatively stationary part of the machine in the movement of said mold member in a direction away from said core member operating automatically to force said side walls outwardly against the resistance of said second-named means. 8. In a machine of the character set forth, the combination of receptacle forming mold and core members, the side walls of said mold member being fulcrumed to swing outwardly and said mold member being movable relative to said core member, means for holding said side walls against outward movement in the molding operation, means for rocking said side walls toward each other, and means engageable with a relatively stationary part of the machine in the movement of said mold member in a direction away from said core member operating automatically to force said side walls outwardly against the resistance of said second-named means. 9. In a machine of the character set forth, the combination of receptacle-forming mold and core members, the side walls of said mold member being movable toward and away from each other and said mold member being movable relative to said core member, means for holding said side walls against outward movement in the molding operation, means for forcing said side walls toward each other, and means surrounding the lower ends of said side walls and engageable with a relatively stationary part of the machine in the movement of said mold member in a direction away from said core member operating automatically to force said side walls outwardly against the resistance of said second-named means. 10. In a machine of the character set forth, the combination of receptacle-forming mold and core members, the side walls of said mold member being movable toward and away from each other and said mold member being movable relative to said core member, means for holding said side walls against outward movement in the molding operation, means for forcing said side walls toward each other, and a member carried by said mold member and relative to which said mold member is movable and operative in the movement of said mold member relative thereto to force said side walls outwardly. 11. In a machine of the character set forth, the combination of receptacle-forming mold and core members, the side walls of said

mold member being movable toward and away from each other and said mold member being movable relative to said core member, means for holding said side walls 5 against outward movement in the molding operation, means engageable with a relatively stationary part of the machine in the movement of said mold member in a direction away from said core member operating automatically to force said walls outwardly, and means engaging said second-named means operating to force said side walls toward each other and against the resistance of which said second-named means operate.

15 12. In a machine of the character set forth, the combination of receptacle-forming mold and core members, the side walls of said mold member being movable toward and away from each other and said mold member being 20 movable relative to said core member, means for holding said side walls against outward movement in the molding operation, means engageable with a relatively stationary part of the machine in the movement of said mold 25 member in one direction operating automatically to force said walls outwardly, and means engaging said second-named means operating to force said side walls toward each other and against the resistance of 30 which said second-named means operate.

18. In a machine of the character set forth, the combination of receptacle-forming mold and core members, the side walls of said mold member being movable toward and away 35 from each other and fulcrumed to rock and said mold member and core member being relatively movable, means for holding said side walls against outward movement in the molding operation, a member extending outwardly beyond said side walls and relative to which said mold member is movable and operative in the movement of said mold member relative thereto to force said side walls outwardly, and spring-tensioned devices engaging 40 said last-named member and said side walls beyond the fulcrums thereof and tending to move said side walls to closed position.

14. In a machine of the character set forth, the combination of receptacle-forming mold 50 and core members, the side walls of said mold member being movable toward and away from each other and fulcrumed to rock and said mold member and core member being relatively movable, means for holding said 55 side walls against outward movement in the molding operation, a member extending outwardly beyond said side walls and relative to which said mold member is movable and operative in the movement of said mold member relative thereto to force said side walls outwardly, bars engaging said side walls beyond their fulcrums and springs associated 60 with said parts and engaging said last-named member for drawing said bars in a direction 65 to rock said side walls to closed position.

15. In a machine of the character set forth, the combination of receptacle-forming mold and core members, the side walls of said mold member being movable toward and away from 70 each other and fulcrumed to rock and said mold member and core member being relatively movable, means for holding said side walls against outward movement in the molding operation, a member extending outwardly beyond said side walls and relative to which said mold member is movable and operative in the movement of said mold member relative thereto to force said side walls outwardly, said side walls beyond 75 their fulcrums being slotted, T-bars in the slots in said side walls, and springs associated with said bars and engaging said last-named member for drawing said bars in a direction to rock said side walls to closed position.

16. In a machine of the character set forth, the combination of receptacle-forming mold and core members, the side walls of said mold member being movable toward and away from each other and said mold member being movable relative to said core member, means for holding said side walls against outward movement in the molding operation, means surrounding the lower ends of said side walls and engageable with a relatively stationary part of the machine in the movement of said mold member in a direction away from said core member operating automatically to force said side walls outwardly, and means engaging said second-named means and said side walls for urging the latter to closed position and against the resistance of which said side walls are forced outwardly by said second-named means.
